INVENTOR.

ARTHUR W. LENFESTEY

BY

Thomas D. Daniels

ATTORNEY.

UNITED STATES PATENT OFFICE

ARTHUR W. LENFESTEY, OF DETROIT, MICHIGAN

HAIRBRUSH

Application filed October 7, 1931. Serial No. 567,388.

My invention relates to a new and useful improvement in a hair brush and has for its object the provision of a hair brush in which the bristles may be mounted so as to rock on their mountings to an outwardly projecting position for use or to a recumbent position so that the brush will be rendered flat and compact for easy carrying in the pocket.

Another object of the invention is the provision of a hair brush which will be light, durable, economically manufactured, compact, and sanitary.

Another object of the invention is the provision of a hair brush having the bristles rockably mounted and provided with a mechanism so that the locking of the bristles in operative position will be automatically effected and their easy and quick release made possible.

Another object of the invention is the provision of a hair brush having bristles rockably mounted in a flexible frame and so arranged that a flexing of the sides of the frame will effect a rocking of the bristles from operative to inoperative position and vice versa.

Other objects will appear hereinafter.

The invention consists in the combination and arrangement of parts hereinafter described and claimed.

The invention will be best understood from a reference to the accompanying drawing which forms a part of this specification and in which,

Fig. 1 is a transverse sectional view taken on line 1—1 of Fig. 2,

Fig. 2 is a top plan view of the invention with one of the end rails shown in section.

Fig. 3 is a fragmentary sectional view taken on line 3—3 of Fig. 2, and,

Fig. 4 is a fragmentary sectional view taken on line 4—4 of Fig. 2.

The invention comprises a supporting frame formed preferably from resilient metal and embodying the side rails 7 and 8 and the end rails 9 and 10. A plurality of bristle supporting bars 11 are rockably mounted on the end rails 9 and 10 by means of the trunnions 12 and 13 which project from the opposite ends of the supporting bars 11. Each of these bars is similarly con-

structed and mounted. In each of the bars 11 there are formed a plurality of spaced slits 14 to provide the tongues or straps 15 which are pressed into off-set relation to the main body of bars 11. The strands 16 of the bristles are passed around the straps 15 and these straps or tongues may then be forced into clamping relation with the bristles, thus securely and quickly mounting the bristles on the bars 11.

Mounted at one end on the inner surface of the side rail 7 is an actuating bar 17 which is connected by the connecting arms 18 to a number of the supporting bars 11. The remaining supporting bars 11 are pivotally connected by the connecting arms 20 to an actuating bar 19 which is attached at one end to the inner surface of the side rail 8 and which projects inwardly therefrom in alignment with the bar 17. As shown in Fig. 3 the ends of the connecting arms 18 and 20 are angularly turned and projected through the bars 17 or 19. The ends 21 and 22 of these actuating bars are reduced and angularly turned to provide latch noses, so that when the rails 7 and 8 are flexed inwardly these reduced ends of the bars 17 and 19 will overlap and latch on each other. The members 17 and 19 are in alignment with each other and when pressed toward each other so that their ends engage the member 17 will ride over the member 19 and thus a latching of the members together will result. When it is desired to release the members an inward pressing of the same will permit the member 17 to be flipped upwardly with the finger whereupon they may be permitted to spring apart into their unlatched positions, as shown in Fig. 1. When these ends are unlatched and the inwardly pressure on the side rails 7 and 8 is released the resiliency of the frame will rock the bars 11 to a position to project the bristles outwardly of the frame into operative position. A chain 23 or other flexible member connects the ends of the bars 17 and 19 so as to limit the withdrawal of the sides 7 and 8.

When the bristles are projected outwardly the brush may be used in the usual manner. When the use of the brush is finished the

sides 7 and 8 may be flexed inwardly, thus rocking the bristles to a recumbent position and locking the same in this position by the latching of the ends of the bars 17 and 19. When in this position the brush will be thin and compact and may be very easily carried in the pocket without any discomfort arising from a pricking of the person by the bristles.

It is believed that the durability and economy of manufacture of the device is apparent, as well as the simplicity with which the device may be operated.

While I have illustrated the preferred form of structure I do not wish to limit myself to the precise details of structure shown, but desire to avail myself of such variations and modifications as come within the scope of the appended claims.

Having thus described my invention what I claim as new and desire to secure by Letters Patent is:

1. A hair brush of the class described, comprising: a frame having oppositely disposed end rails and oppositely disposed resilient side rails; a plurality of spaced bristle supporting bars extending between and rockably mounted at their opposite ends on said end rails; a pair of actuating bars, each mounted on one of said side rails and projecting inwardly therefrom, said actuating bars being in alignment; means for connecting each of said actuating bars to said bristle supporting bars, for effecting a rocking of said bristle supporting bars upon inwardly flexing of said side rails.

2. A hair brush of the class described, comprising: a frame, having oppositely disposed end rails and oppositely disposed side rails; a plurality of bristle supporting bars extending between and rockably mounted at their opposite ends on said end rails; an actuating bar on each of said side rails and projecting inwardly of said frame, said bars being in alignment with each other and engageable at their inner ends upon inward flexing of said side rails for latching said side rails against outward flexing; and means connecting said bristle supporting bars to said actuating bars for effecting a rocking of the same on their axes upon inward and outward movement of said actuating bars.

3. A hair brush of the class described, comprising: a frame, having oppositely disposed end rails and oppositely disposed resilient side rails; a plurality of spaced bristle supporting bars extending between and rockably mounted at their opposite ends on said end rails; and means connecting to each of said bars for effecting a rocking of the same upon inward and outward flexing of said side rails.

In testimony whereof I have signed the foregoing specification.

ARTHUR W. LENFESTEY.
